US00D878279S

(12) **United States Design Patent** (10) Patent No.: **US D878,279 S**
MacNeil et al. (45) Date of Patent: **** Mar. 17, 2020**

(54) **VEHICLE CUP HOLDER CELL PHONE MOUNT**

(71) Applicant: **MACNEIL IP LLC**, Bolingbrook, IL (US)

(72) Inventors: **David F. MacNeil**, Fort Lauderdale, FL (US); **David S. Iverson**, Oak Brook, IL (US)

(73) Assignee: **MACNEIL IP LLC**, Bolingbrook, IL (US)

(**) Term: **15 Years**

(21) Appl. No.: **29/710,629**

(22) Filed: **Oct. 24, 2019**

Related U.S. Application Data

(60) Division of application No. 29/707,213, filed on Sep. 26, 2019, which is a continuation-in-part of application No. 29/668,090, filed on Oct. 26, 2018, now Pat. No. Des. 873,205.

(57) **CLAIM**

We claim the ornamental design for a vehicle cup holder cell phone mount, as shown and described.

DESCRIPTION

FIG. 1 is a top front perspective view of a first configuration of our design in which two of four shells of our design have been assembled to a base of our design, a pier, cell phone bracket, cell phone and power cord being shown in dotted line as environmental structure;

FIG. 2 is front top perspective view of a second configuration of our design, in which no shells of our design have been assembled to the base, the pier and cell phone bracket being shown in dotted line as environmental structure;

FIG. 3 is a front view of our design as configured in FIG. 2; FIG. 4 is a right side view of our design as configured in FIG. 2;

FIG. 5 is a left side view of our design as configured in FIG. 2;

FIG. 6 is a rear view of our design as configured in FIG. 2; FIG. 7 is a top view of our design as configured in FIG. 2; FIG. 8 is a bottom view of our design as configured in FIG. 2;

FIG. 9 is a top front perspective view of a third configuration of our design, in which first, second, third and fourth shells have been assembled to the base;

FIG. 10 is a front view of our design as configured in FIG. 9;

FIG. 11 is a top view of our design as configured in FIG. 9; FIG. 12 is a bottom view of our design as configured in FIG. 9;

FIG. 13 is a top front exploded perspective view of our design as configured in FIG. 9;

FIG. 14 is a bottom rear exploded perspective view of our design as configured in FIG. 9;

FIG. 15 is a front-to-rear axial sectional view of our design as configured in FIG. 9;

FIG. 16 is a bottom perspective view of a first shell forming a portion of our design;

FIG. 17 is a side view of the first shell;

FIG. 18 is a bottom view of the first shell;

FIG. 19 is a top view of the first shell;

FIG. 20 is a top perspective view of the first shell;

FIG. 21 is a partial sectional detail of the lip region of the first shell taken along 21-21 in FIG. 20;

FIG. 22 is a bottom perspective view of a second shell forming a portion of our design;

FIG. 23 is a side view of the second shell;

FIG. 24 is bottom view of the second shell;

FIG. 25 is a top view of the second shell;

FIG. 26 is a top perspective view of the second shell;

FIG. 27 is a partial sectional detail of the lip region of the second shell taken along 27-27 in FIG. 26;

FIG. 28 is a bottom perspective view of a third shell forming a portion of our design;

FIG. 29 is a side view of the third shell;

FIG. 30 is bottom view of the third shell;

FIG. 31 is a top view of the third shell;

FIG. 32 is a top perspective view of the third shell;

FIG. 33 is a partial sectional detail of the lip region of the third shell taken along 33-33 in FIG. 32;

FIG. 34 is a bottom perspective view of a fourth shell forming a portion of our design;

FIG. 35 is a side view of the fourth shell;

FIG. 36 is bottom view of the fourth shell;

FIG. 37 is a top view of the fourth shell;

FIG. 38 is a top perspective view of the fourth shell; and,

FIG. 39 is a partial sectional detail of the lip region of the fourth shell taken along 39-39 in FIG. 38.

The dotted lines shown in the drawings illustrate environment and portions of the vehicle cup holder cell phone mount that form no part of the claimed design.
